(57) **CLAIM**

The ornamental design for a lens for camera, as shown and described.

DESCRIPTION

The file of this patent contains at least one drawing executed in color. Copies of this patent with color drawings will be provided by the United States Patent and Trademark Office upon request and payment of the necessary fee.

FIG. 1 is a front view of a lens for camera showing the new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a front, top perspective view thereof; and,

FIG. 8 is a rear, bottom perspective view thereof.

The broken lines shown in the drawings depict portions of the lens for camera that form no part of the claimed design.
